Inventor:

Adam H. Rennie

United States Patent Office.

ADAM H. RENNIE, OF BINGHAMTON, NEW YORK.

Letters Patent No. 63,095, dated March 19, 1867.

IMPROVED BEDSTEAD FASTENING.

The Schedule referred to in these Letters Patent and making part of the same.

TO ALL WHOM IT MAY CONCERN:

Be it known that I, ADAM H. RENNIE, of Binghamton, in the county of Broome, and State of New York, have invented a new and improved Mode of Connecting and Fastening Bedsteads or similar constructions together; and I do hereby declare that the following is a full and exact description thereof, reference being had to the accompanying drawings, making a part of this specification, in which—

Figure 1 is an inside view of a connected corner section.

Figures 2 and 3 are disconnected sections, showing the oblique dowel pins and their corresponding holes in the posts.

Figure 4 represents the guide-block or templet, which is dependently connected with the construction of my improvement.

Similar letters of reference indicate corresponding parts in each figure.

The object of this invention is to construct a bedstead which shall possess the qualities of stability, simplicity, and cheapness, with joints which shall be impervious to insects, and dispensing with all metallic appliances, with the exception of a single clasp at each joint.

To accomplish this, I insert in the end of the rail A three or more dowel pins, *b b b*, extending obliquely downwards from the face of the joint. Said pins are fitted to corresponding holes in the posts, so that an increase of weight upon the rail increases the adhesion of the connection. For the purpose of increasing the lateral stiffness of the joints, I insert two of the dowel pins on a line in the end of the rail, and one or more as far from the side of said line as consistent with the thickness of the material. The holes for the dowel pins are made by means of a guide-block or templet, represented by fig. 4. The operation is accomplished by placing it in the proper position on the end of the rail, where it is secured from slipping by the steady-points P P P. The holes are then bored, those in the templet guiding the bit in the desired direction; it is then detached, and the opposite side placed upon the post and the holes bored in the same manner. In order to give still more security to the joints, I attach an eccentric clasp, D, which works on a pin in the post. By this means the joints are drawn more tightly together, making it impossible for insects to enter. When the bedstead is to be taken apart, the clasp can be detached by simply unlocking and slipping it off from the pin. The rails are then detached by raising them from their oblique bearings in the posts.

I am aware that there are fastenings for bedsteads which are similar in some respects to mine, most of them having iron attachments, while some are constructed of wood with tenons of the same material, the lower or bearing edge of which is cut on an angle with a corresponding mortise. All such arrangements are liable to get out of order. The joints soon become loose, as they are not of sufficient strength to endure the lateral strain to which they are more or less liable. My improvement obviates all these difficulties. The dowel pins are selected of the best material, and so arranged as to give the joints all the requisite stiffness, while the eccentric clasp draws the post and rail so closely together that it resembles a solid substance. It is more easily manufactured, more durable, "and can be more economically and beneficially enjoyed by the public." I therefore disclaim all similar devices and confine myself to the novel features of my improvement.

What I claim, and desire to secure by Letters Patent, is—

The mode of constructing, arranging, and combining oblique dowel pin joints with the eccentric clasp D, substantially in the manner herein described and represented.

ADAM H. RENNIE.
